UNITED STATES PATENT OFFICE.

LAUREN T. TUTTLE, OF SONOMA COUNTY, CALIFORNIA.

AUTOMATIC ADVERTISING-DISPLAY MACHINE.

1,144,621.

Specification of Letters Patent. Patented June 29, 1915.

Application filed November 13, 1913. Serial No. 800,824.

To all whom it may concern:

Be it known that I, LAUREN T. TUTTLE, a citizen of the United States, and a resident of the county of Sonoma, State of California, have invented a new and useful Automatic Advertising-Display Machine, of which the following is a specification.

The mechanism is shown by the drawings attached hereto.

10 The purpose of this device is to show or display advertising, pictures or other matter in a convenient form to be applied particularly on or over the sales counter of a store or in the show window of a store or elsewhere.

15 The purpose is to provide a device which will facilitate the advertising or display of a number of different subjects in the same device and in such manner that the copy for 20 each subject may be changed independently one of the other; also in such manner that only one subject will be displayed at a time.

25 The theory upon which the inventor has constructed his machine is that when a purchaser is in a store, for instance, a grocery store, that is the psychological moment to suggest to the prospective purchaser that he purchase sundry articles which are contained in the stock of that store and this 30 device will operate by way of a mental suggestion at the moment when the purchaser is either in the act of buying supplies or is most likely to invest. It is to act as the last word, a sort of automatic salesman 35 which will call to mind many impressions regarding goods previously advertised through other means.

40 On viewing this machine in operation, one sees a cylindrical drum mounted on a pedestal. There is an opening in the front of the cylindrical drum with electric lights and reflector running longitudinally above the opening. In this opening appear at intervals advertisements, pictures or other matter.

45 The details of construction and mode of operation of my device are more readily understood by having reference to the accompanying drawings in which similar letters and figures refer to similar parts throughout the several views.

50 Figure 1 illustrates a front view of the machine in perspective. Fig. 2 is an illustration in perspective of the outer case (a) mounted upon the pedestal (c); and the

outer case (a) is broken away to show the inner drum (b); a number of the preferably concave faces (1), of the inner drum (b); and a portion of the stopping and releasing device (4). Fig. 3 is a cross-section of a portion of the releasing and stopping device. Fig. 4 is a cross-sectional view of the entire apparatus. Fig. 5 is a view of the stopping and releasing device looking from above and also showing a cross-section of the inner drum (b) and the outer case (a). Fig. 6 is a cross-sectional view particularly of a portion of the device for operating and a portion of the outer case (a) and inner drum (b).

70 The pedestal (c) and outer case (a) constitute the framework of the machine.

The inner drum (b) is a cylinder revolving on bearings (3) inside of the outer case (a), as shown in Figs. 1, 2, 4 and 5.

75 The cylinder or drum (b) constituting a carrier, has mounted on its face, preferably twelve concave faces. These faces (1) are constructed so as to receive and retain advertisements, pictures or other matter, as 80 illustrated at 29, Fig. 6.

85 Referring to Fig. 4, drum (b) is operated by preferably a chain-belt (12) passing over sprocket (23) and pulleys (14), (14^a) (15), (15^a), and chain-tightener (18). Rigidly attached to chain-belt (12) is a lug (17) which when traveling over pulley (15) successively engages point (30) as shown in Fig. 6 and propels drum (b) on its bearings (3) preferably one-twelfth of the circumference of the said drum (b), as shown in Fig. 4.

90 Referring to Figs. 2, 4 and 6, near the periphery of one of the ends of drum (b) are located small holes (2) situated preferably 30 degrees apart.

95 Referring to Fig. 5, situated above and to one side of pulley (15) is a cam (9) mounted on lever (28), pivoted at (31). Pivoted to lever (28) at (34) is lever (4) mounted in 100 slideable bearings (11). The outer end of lever (4) is formed preferably at right angles as indicated in Fig. 3. On the end of lever (4) is pin (6) as particularly shown in Fig. 3.

105 Referring to Fig. 5, as lug (17) rides up and over pulley (15), it engages the curved side of the outer end of cam (9) and forces cam (9) over as shown by dotted lines, this causes lever (4) to slide in its bearings (11).

and forces spring (5) outwardly toward the inner surface of the outer case (a). Pin (6) is so positioned on lever (4) that when lever (4) is in its outward position, 5 pin (6) will be directly opposite to one of the holes (2), as shown in Fig. 4, in the end of drum (b).

Referring to Fig. 5, when lug (17) has 10 passed cam (9) spring (5) forces lever (4) inwardly and causes lever (28) to move inwardly and against stop-pin (10), and causes pin (6) to engage with hole (2), Fig. 4, thus locking drum (b) in such position that one of its concave faces (1) will be directly opposite aperture (d).

Referring to Fig. 5, the object of stop-pin (10) is to hold cam (9) in the proper position for engagement with lug (17).

Referring to Fig. 4, after lug (17) has 20 passed pulley (15^a) and (14^a) and has traveled down and around sprocket (23) and again to upper portion of pulley (15), then, referring to Fig. 5, it again engages the outer portion of cam (9) thereby forcing 25 lever (4) back and thus disengaging pin (6) from hole (2) as shown by dotted lines.

Referring to Fig. 6, the moment that pin (6) is disengaged from hole (2), lug (17) 30 engages at point (30) with drum (b) and propels it on bearings (3) thus bringing another concave face (1) directly opposite opening (b) as shown in Fig. 4.

Referring to Fig. 4, sprocket (23) is mounted on shaft (32) and is operated by 35 pulley (22) also mounted on shaft (32). Pulley (22) is operated by motor (24) through pulleys (20) and (33). Attached to pulley (20) is a fly-wheel (21), the object of which is, by its momentum, to assist the 40 motor in starting the movement of drum (b), when the lug (17) engages with point (30). Attached to outer case (a) and directly above aperture (d) is located a reflector (7) in which are located preferably 45 an electric light or electric lights; the purpose of the reflector and the light or lights, being to illuminate preferably concave faces (1) as each successively moves to position directly opposite aperture (d).

50 Referring to Fig. 1, in order to afford a proper setting for the advertising as it appears in aperture (d) a frame or shadow box (8) is mounted surrounding aperture (d) and upon the case (a).

55 Referring to Fig. 4, in outer case (a) directly above pulleys (15) and (15^a) is a preferably rectangular opening (18) which allows lug (17) access to drum (b).

60 Referring to Fig. 6, pulleys (15), (15^a), (14) and (14^a) are situated in a suitable

opening in blocks (25), (26) and (27) which form the upper portion of the pedestal (c).

As to materials, this machine may be constructed of any suitable materials.

I claim:

1. In an advertising display machine, a carrier, a driving belt therefor, a locking pin adapted to engage a part on the carrier, a cam, and a lug carried by the driving belt adapted to engage said cam to effect the disengagement of the pin.

2. In an advertising display machine, a carrier, a driving belt therefor, a lock adapted to engage a part on the carrier, a spring for effecting engagement of the lock, and means for effecting disengagement of the lock comprising a cam operatively associated therewith adapted to be engaged by a part on the driving belt, substantially as described.

3. In an advertising display machine, a hollow pedestal open at its upper end, a rotatable carrier supported above the same, and means for periodically shifting the carrier comprising engaging portions on the 85 periphery thereof, and a driving belt mounted and movable within the pedestal having an upper run bridging said open upper end adjacent to the carrier of approximately the length of the predetermined shifting movement of the carrier, said belt carrying a part adapted to engage the engaging portions on the carrier.

4. In an advertising display machine, a hollow pedestal, a rotatable carrier supported above the pedestal, and means for periodically shifting the carrier comprising a driving belt mounted and movable within the pedestal adapted to engage complementary parts of the carrier, and supporting 95 and guiding means for the belt causing the same to assume an approximately T-formation the length of the upper run of the T determining the movement of the carrier, substantially as and for the purpose described.

5. In an advertising display machine, the combination with a carrier, of driving means therefor comprising a belt having a part adapted to engage a complementary part on the carrier to shift the carrier at predetermined intervals in the movement of the belt, and a lock adapted to hold the carrier in its positions of rest, said lock being arranged to be engaged and released by the 110 carrier engaging part on the driving belt.

LAUREN T. TUTTLE.
